UNITED STATES PATENT OFFICE.

HARRY GERSTEIN, OF ROCKAWAY, NEW YORK, ASSIGNOR TO HARRY GERSTEIN, FRANK GERSTEIN, AND ABRAHAM GERSTEIN, COPARTNERS, DOING BUSINESS AS GERSTEIN BROTHERS.

CUTTING MACHINE.

Application filed January 6, 1925. Serial No. 756.

This invention relates to fabric cutting machines and particularly to machines of the general class employed in cutting bias strips from a tube or sleeve of material.

5 An important object of the invention is to provide in a machine of the character mentioned a generally improved combination of elements so related and arranged as to render the machine reliable, dependable, accurate and economical in its operation.

10 Other objects and certain advantages of the invention will become apparent from the following description when taken in connection with the accompanying drawings in 15 which—

Figure 1 is a plan view of the machine embodying my invention.

Figure 2 is a view in elevation of the machine.

20 Figure 3 is a front elevation of a take-up mechanism.

Figure 4 is a view in elevation of the take-up mechanism as viewed from the left in Figure 3.

25 Figure 5 is a transverse sectional view taken on line 5—5 of Figure 3.

Figure 6 is a fragmental view of a mandrel showing in elevation a tension device attached thereto.

30 Figure 7 is a view of the tension device as seen from the left in Figure 6.

Figure 8 is a detail view of a drive pulley partly in elevation and partly in section.

35 Figure 9 is a view similar to that of Figure 8 showing details of a braking device.

In the drawings wherein for the purpose of illustration is shown what I consider the preferred form of my invention, the numeral 5 indicates an elongated mandrel suitably supported in a horizontal plane by means of an arm 6 secured to a suitable anchor 7. The mandrel 5 presents, at its forward end, a curvilinear face 8 adjacent to which is arranged a spreader 9 adapted to guide the tube or sleeve of material 10 on to the mandrel during the operation of the machine. In order to maintain the sleeve of material taut so that the same will snugly hug or engage the upper surface of the mandrel, I have provided a tensioning device indicated, as a whole, by the numeral 11. This tension device comprises a plurality of depending arms 12, preferably three in number, which are secured to the mandrel 5. To each of

these arms there is slidably connected a movable support 13, the support being provided with an elongated slot 14 through which a pair of rivets or pins 15 pass, the rivets being carried by the stationary arm 12. To the lower ends of the supports 13 are connected 55 a pair of rollers 16 which, when the machine is operating, are enclosed within the tube of material 10 and engage the same as it passes onto and over the mandrel. In order to provide for the proper tensioning of the 60 material through the instrumentality of the rollers 16, I employ a plurality of tension springs 17 the tension of which may be varied by means of thumb-screws 18 carried by the stationary arms 12. These springs 70 are connected at their upper ends to the thumb-screws 18 and are secured at their lower ends to pins 19 carried by the movable supports 13. It will be appreciated, therefore, that the pressure or tensioning effect 75 exerted upon the material by the rollers 16 may be varied by increasing or decreasing the tension of the several springs 17 as desired. For example, if it is desired to increase the tension exerted, the tension of the 80 springs 17 is decreased, whereas, on the other hand, if it is desired to decrease the tension exerted upon the material the thumb screws 18 are so adjusted as to increase the tension of the springs. 85

The material 10, in tubular form, is carried by a supply reel 20, comprising a driven shaft 21, upon which is rotatably mounted a pair of discs 22, between which the roll of material is adapted to fit. The shaft 21 is 90 journaled within projecting arms 23 of a rotatable reel holder 24, the reel holder being provided with a shaft 25 journaled in a suitable support or bearing 26. To the shaft 25 there is connected a sprocket 27, 95 operatively connected by means of a sprocket chain 28 to a similar sprocket 29 carried by a drive shaft 30, the drive shaft being provided with a pulley 31 adapted for connection with a suitable source of 100 power such as an electric motor, not shown. Notwithstanding the fact that the discs 22 are loosely mounted upon the shaft 21 there exists a certain amount of friction between the shaft and the discs. As a result of this friction I am enabled to facilitate the turning of the roll of material by positively driving the shaft 21. This positive drive is af- 105

forded through the instrumentality of a power transmission comprising a sprocket 32 connected to the shaft 30, the sprocket 32 being in turn connected by means of a 5 sprocket chain 33 to a sprocket 34 loosely mounted upon the shaft 25. The sprocket 34 in turn carries a similar sprocket 35 which is connected, by means of a sprocket chain 36, to a sprocket 37 carried by a shaft 10 38 journaled to the reel holder 24. This shaft carries a beveled gear 39 meshing with a similar beveled gear 40 secured to the shaft 21. It will be appreciated from the preceding 15 description that as the reel holder 24 is rotated the shaft 21 is simultaneously rotated, the rotation of the latter being in the direction of the rotation of the discs 22 as the material is unwound therefrom. By mounting the discs 22 loosely upon the shaft 20 21 the necessity for elaborate compensating means, due to the increase in speed and rotation of the reel 20 as the diameter of the roll of material decreases, is eliminated. In this connection it may be well to point out that 25 the material, upon leaving the reel 20, travels at a constant rate of speed, as will later become apparent, and so also is the shaft 21 driven at a constant rate of speed. If the roll of material carried by the reel 30 20 is of such a diameter, when the reel is completely filled, for example, that the reel rotates at the same rate of speed as the shaft 21 no relative movement between the reel 20 and shaft 21 will exist. As the diameter 35 of the roll of material decreases, however, the speed of rotation of the reel 20 increases for the reason that the lineal travel of the material leaving the reel remains constant but the speed of rotation of the shaft 21 remains constant. When the speed of rotation of the reel 20 is first increased with 40 respect to the shaft 21 the speed differential is very slight and the increased tension set up within the material as it leaves the roll is, therefore, almost negligible. As the diameter of the roll of the material is further decreased the speed differential becomes greater and the tension exerted in 45 the material leaving the reel is correspondingly increased, but not even when the diameter of the material is reduced to a minimum is there a sufficient increase in tension of the material leaving the roll to impair the accuracy in the operation of the machine inasmuch as the increase in speed of rotation of the reel 20 over the speed of the shaft 21 is relatively small.

In order to provide a simple yet effective 50 means for braking the shaft 21 to prevent any undue variation in speed as a result of backlash between the driving connections from the shaft 30, I employ at the outer end of each of the arms 23 a variable pressure device indicated as a whole by the numeral 41. Each of these devices comprises a screw- 55

threaded plunger 42 adapted to engage a screw-threaded ferrule 43 within which is arranged a compression spring 44 and a suitable friction or packing material 45 arranged in contact with the shaft 21. When 70 the screw-threaded plunger 42 is so run down as to exert a greater compression force against the spring 44 a similar increase in pressure applied to the shaft 21 through the backing or friction material 45, is afforded, whereas, on the other hand, by proper adjustment of the plunger 42 the braking effect of the packing material upon the shaft may be decreased. The proper adjustment 75 of the plunger 42 may be determined, as 80 will be readily appreciated, by observing the action of the machine and particularly the driving connections afforded between the shafts 21 and 30 during the operation of 85 the machine.

As the material is passed onto the mandrel 5 the same is cut into a bias strip 46 by means of a rotatable knife 47 operatively connected to an electric motor 48 carried by 90 a suitable bracket 49 secured to the mandrel 5, the bracket being so arranged that the cutting edge of the knife lies in a plane passing through the mandrel at right angles to a series of rollers embodied in a take-up 95 mechanism 50 located in proximity to the mandrel 5 and hereinafter more particularly described.

The take-up mechanism 50, above mentioned, is employed as a means for removing 100 the strip of material 46 from the mandrel as it is severed or cut from the tube of material by the motor driven knife 47. This take-up device comprises a frame 51 having vertically disposed standards 52 to 105 which is journaled an intermediate shaft 53 carrying an intermediate roller 54 adapted to engage upper and lower rollers 55 and 56, respectively. The upper roller 55 is carried by a shaft 57 journaled in vertically movable bearings 58 arranged 110 within guides or channels 59 formed in the standards 52. These bearings are normally urged downwardly by means of compression springs 60, the lower ends of which 115 engage the bearings 58 whereas the upper ends engage cover plates or abutments 61 carried by the standards and secured thereto through the instrumentality of lag bolts 62 or the like. The lower roller is carried 120 by a shaft 63 which is journaled in vertically movable bearings 64, similar to those indicated by the numeral 58 and operating within the guides 59 formed in the standards 52. This roller is normally held in 125 contact with the roller 54 by means of a pair of cams 65 pivotally connected to the standards 52 and having arms 66 projecting therefrom which are connected together at their outer ends by means of a rod 67 which 130 enables both cams to be operated simultane-

ously to disengage the roller 56 from the roller 54 or to move the same into contact therewith as desired. In order to move the roller 55 out of engagement with the roller 54 I have provided a similar pair of cams 68 which are pivotally connected to the standards 52 and are provided with arms 69 connected together at their outer ends by means of a rod 70 which enables the cams to be operated simultaneously. The cams 65 and 68 are employed as a means for readily separating the rollers 55 and 56 from the intermediate roller 54 to enable the strip of material at the beginning of the cutting operation to readily pass over the rolls as indicated in Figure 5. After the strip of material has been threaded into the take-up mechanism the cams 65 and 68 are so operated as to permit the upper and lower rollers 55 and 56 to move into engagement with the material as indicated, these rollers being held respectively in their operative positions by means of the springs 60 and the cams 65. Before the material is threaded into the take up mechanism, it is threaded or passed through a suitable guide 71 associated with the take-up mechanism and arranged intermediate the rollers thereof and the mandrel 5. This guide comprises a pair of arms 72 which are carried by the standards 52 and to which are connected a plurality of rods 73, 74, and 75. This guide, as will be readily appreciated, affords a means for insuring the entrance of the strip of material into the take-up mechanism in a flat condition thereby preventing wrinkling or creasing of the same.

The several rollers 54, 55 and 56 derive their power of rotation from the power shaft 30, this shaft being connected to the shaft 53 through the instrumentality of a series of gears 76, 77 and 78, the former of which is connected to the shaft 30 whereas the latter is connected to the shaft 53. The shaft 53 in turn is provided with a gear 79 adapted to mesh with similar gears 80 and 81 carried, respectively, by the shafts 57 and 63. By the arrangement of gearing herein shown the rollers 54, 55 and 56 are rotated in the direction of the arrows shown thereon thus causing the material to pass through the take-up mechanism as indicated whereupon it may be wound around a suitable reeling mechanism not shown, arranged at the rear of the take-up mechanism and adapted for connection with a pulley 82 carried by the shaft 53. If an ordinary roll or reel is employed to receive the material and is driven by the pulley 82 it becomes necessary to provide a yielding engagement between the pulley 82 and the shaft 53 to compensate for the necessary decrease in speed of the reeling device as the diameter of the roll of material received thereby is increased and to this end I frictionally con-

nect the pulley 82 to the shaft 53. This friction connection is afforded by means of a friction or packing material 83 carried by the hub portion 84 of the pulley, the friction material being adapted to be urged into engagement with the shaft 53 through the instrumentality of an adjustable screw 85 or the like. By running the screw 85 up or down within the screw-threaded passage 86, into which it fits, any desired amount of friction may be afforded between the shaft 53 and the pulley, the amount of friction required being dependent, of course, upon certain conditions incident to the operation of the machine as will be readily understood.

In order to maintain the bias strip 46 in a more or less taut, and incidentally flat, condition intermediate the mandrel 5 and guide 71 I provide a tensioning roll 87. This roll is journaled at one end in an arm 88 carried by the mandrel 5 and is at its opposite end journaled in a relatively long and more or less yieldable arm 89 suitably secured to the take-up mechanism 50. The arm 89, being yieldable, permits the roll 87 to move slightly up and down as the tension in the strip 46 varies and consequently maintains the material in an intimate engagement with the mandrel 5 particularly in the vicinity of the knife 47 thus insuring a straight edge cut.

Having thus described my invention I claim:

1. A cutting machine comprising a mandrel adapted to receive thereupon a moving tube of material to be cut, tensioning means suspended from said mandrel and adapted to engage said tube of material and exert thereupon a tensioning effect, and resilient suspension means suspending said tensioning means and tending to lift the same toward said mandrel.

2. A cutting machine comprising a mandrel adapted to receive thereupon a moving tube of material to be cut, tensioning means suspended from said mandrel and adapted to engage said tube of material and exert thereupon a tensioning effect, resilient suspension means suspending said tensioning means and tending to lift the same toward said mandrel, means for moving the tube of material progressively onto said mandrel, and means for cutting the material into a strip, the means employed to move the material onto the mandrel being employed also to remove the strip of material from the mandrel.

3. A cutting machine comprising a mandrel adapted to receive thereupon a moving tube of material to be cut, and tensioning means suspended from said mandrel and adapted to engage said material and exert thereupon a tensioning influence, said tensioning means comprising a roller arranged longitudinally of said mandrel and spring devices yieldably suspending said roller and

tending to lift the same toward said mandrel.

4. A cutting machine comprising a mandrel adapted to receive thereupon a moving tube of material to be cut, tensioning means suspended from said mandrel and adapted to engage said material and exert thereupon a tensioning influence, said tensioning means comprising a roller arranged longitudinally of said mandrel, tensioning devices yieldably supporting said roller and tending to lift the same toward said mandrel and means for adjusting the tensioning devices whereby the influence exerted upon said material by said tensioning means is varied.

5. A cutting machine comprising a mandrel adapted to receive thereupon a moving tube of material to be cut, tensioning means suspended from said mandrel and adapted to engage said material and exert thereupon a tensioning influence, said tensioning means comprising a roller arranged longitudinally of said mandrel and yieldably supported with respect thereto, means for varying the tensioning influence exerted upon said material by said tensioning device, and a spreader arranged at one end of said mandrel to guide the material onto the mandrel and over said tensioning device.

30 6. A cutting machine comprising a mandrel, a support adapted to support a roll of material in tubular form to be cut into a bias strip, a cutting device associated with said mandrel for cutting the material into a bias strip, means for moving the material from its support onto said mandrel to be cut into a bias strip and for removing said bias strip from said mandrel, said means being in the form of an intermediate roller associated with upper and lower rollers and adapted to normally contact therewith, a plurality of cams for moving the upper and lower rollers out of contact with the intermediate roller whereby the strip of material may be threaded over said rollers.

7. A cutting machine comprising a mandrel, a support adapted to support a roll of material in tubular form to be cut into a bias strip, a cutting device associated with said mandrel for cutting the material into a bias strip, means for moving the material from its support onto said mandrel to be cut into a bias strip and for removing said bias strip from said mandrel, said means being in the form of an intermediate roller associated with upper and lower rollers and adapted to normally contact therewith, a plurality of cams for moving the upper and lower rollers out of contact with the intermediate roller whereby the strip of material may be threaded over said rollers, and means arranged intermediate said rollers and mandrel for retaining the strip of material in a flat condition as it passes over said rollers.

8. A cutting machine comprising a man-

drel, a reel for supporting a roll of material in tubular form to be cut, a cutting device associated with said mandrel for cutting the material into a bias strip, a take-up mechanism adapted to be so operated as to feed the material to be cut onto said mandrel and to remove the strip of material therefrom, a reel support supporting said reel, means for rotating said reel support about one axis as the material is fed onto said mandrel, and means for rotating said reel about another axis simultaneously with the rotation of said reel support, and friction means for retarding the rotation of said reel.

9. A cutting machine comprising a mandrel, a reel adapted to carry a roll of material in tubular form to be cut into a bias strip, means associated with said mandrel for cutting the material into a bias strip, a take-up mechanism in the form of a plurality of rollers over which the strip of material passes for moving the material onto said mandrel and for removing the strip of material therefrom, means for rotating said rollers, and means located intermediate said mandrel and said take-up mechanism for maintaining the material in intimate engagement with said mandrel.

10. A cutting machine comprising a mandrel, a reel adapted to carry a roll of material in tubular form to be cut into a bias strip, means associated with said mandrel for cutting the material into a bias strip, a take-up mechanism in the form of a plurality of rollers over which the strip of material passes, for moving the material onto said mandrel and for removing the strip of material therefrom, means for rotating said rollers, and means in the form of a yieldably supported roller located intermediate said mandrel and said take-up mechanism for maintaining the material in intimate engagement with said mandrel.

11. A cutting machine comprising a mandrel, a reel adapted to carry a roll of material in tubular form to be cut into a bias strip, means associated with said mandrel for cutting the material into a bias strip, a take-up mechanism in the form of a plurality of rollers over which the strip of material passes for moving the material onto said mandrel and for removing the strip of material therefrom, means for rotating said rollers, means for simultaneously rotating said reel about different axes, means for retarding the rotation of said reel about one of said axes, means arranged intermediate said take-up mechanism and mandrel for maintaining the strip of material in a flat condition as it passes over said rollers, and a tension device associated with said mandrel for retaining the tube of material in a taut condition as it passes onto said mandrel.

12. A cutting machine comprising a mandrel, a reel adapted to carry a roll of material in tubular form to be cut into a bias strip, means associated with said mandrel 5 for cutting the material into a bias strip, a take-up mechanism in the form of a plurality of rollers over which the strip of material passes for moving the material onto said mandrel and for removing the strip of material therefrom, means for rotating said rollers, means for simultaneously rotating said reel about different axes, means for retarding the rotation of said reel about one of said axes, means arranged intermediate 10 said take-up mechanism and mandrel for maintaining the strip of material in a flat condition as it passes over said rollers, and a tension device associated with said mandrel for retaining the tube of material in a 15 taut condition as it passes onto said mandrel, said tensioning device comprising a plurality of rollers yieldably supported by said mandrel.
13. A cutting machine comprising a mandrel, a reel adapted to carry a roll of material in tubular form to be cut into a bias strip, means associated with said mandrel for cutting the material into a bias strip, a take-up mechanism in the form of a plurality 20 of rollers over which the strip of material passes for moving the material onto said mandrel and for removing the strip of material therefrom, means for rotating said rollers, means for simultaneously rotating said reel about different axes, means for retarding the rotation of said reel about one 25 of said axes, means arranged intermediate said take-up mechanism and mandrel for maintaining the strip of material in a flat condition as it passes over said rollers, a tension device associated with said mandrel for retaining the tube of material in a 30 taut condition as it passes onto said mandrel, said tensioning device comprising a plurality of rollers suspended from said mandrel and a plurality of springs associated with said rollers and adapted for adjustment to vary the tensioning influence of said 35 rollers upon said tube of material, and a spreader arranged at the forward end of said mandrel and adapted to guide the tube of material onto said mandrel and over said 40 tensioning device.
14. A cutting machine comprising a mandrel, a reel adapted to carry a roll of material in tubular form to be cut into a bias strip, means associated with said mandrel for cutting the material into a bias strip, a take-up mechanism in the form of a plurality 45 of rollers over which the strip of material passes for moving the material onto said mandrel and for removing the strip of material therefrom, means for rotating said rollers, means for simultaneously rotating 50 said reel about different axes, means for retarding the rotation of said reel about one of said axes, means arranged intermediate said take-up mechanism and mandrel for maintaining the strip of material in a flat condition as it passes over said rollers, a tension device associated with said mandrel for retaining the tube of material in a 55 taut condition as it passes onto said mandrel, said tensioning device comprising a plurality of rollers suspended from said mandrel and a plurality of springs associated with said rollers and adapted for adjustment to vary the tensioning influence of said 60 rollers upon said tube of material, and a spreader arranged at the forward end of said mandrel and adapted to guide the tube of material onto said mandrel and over said 65 tensioning device.

In testimony whereof, I have affixed my 70
signature to this specification.

HARRY GERSTEIN.
